CLAIM

The ornamental design for an ergonomic arm support for a chair, as shown and described.

DESCRIPTION

FIG. 1 is a front perspective view of the ergonomic arm support for a chair showing my new design, the broken line depiction of the chair being for illustrative purposes only and forming no part of the claimed design;

FIG. 2 is a top plan view of the ergonomic arm support;

FIG. 3 is a front elevational view of the ergonomic arm support;

FIG. 4 is a side elevational view of the ergonomic arm support in a first position;

FIG. 5 is a bottom view of the ergonomic arm support; and,

FIG. 6 is a side elevational view of the ergonomic arm support in a second position.
